WILLIAM H. SCHOONMAKER, OF MONTCLAIR, NEW JERSEY.

INTERNAL-COMBUSTION ENGINE.

1,182,803.

Specification of Letters Patent.

Patented May 9, 1916.

Application filed October 25, 1911. Serial No. 656,730.

To all whom it may concern:

Be it known that I, WILLIAM H. SCHOONMAKER, a citizen of the United States, and a resident of Montclair, county of Essex, 5 and State of New Jersey, have invented certain new and useful Improvements in Internal-Combustion Engines, of which the following is a full, clear, and exact description.

10 The object of my invention is to provide a means for starting internal combustion engines of the four-cycle automobile type, by means of which the machine may be brought up to normal speed with certainty 15 and without violent shocks to the engine and also an apparatus which will be comparatively simple in its organization, making it practicable for automobiles of all classes.

To this end the invention resides in a 20 peculiar arrangement by which I am enabled to bring about the initial movement of the engine at the operation of air pressure or other fluid under pressure, which serves not only to turn the engine over, but to bring 25 into action an excellent starting system, this system in turn operating the engine until the normal operation of the engine under the carburetor is taken up. In this manner I am enabled to pass successively from one 30 stage to the other with a very easy action and bring the engine up to normal speed and normal operation gradually, reliably and without shocks or jars on the moving parts.

35 The invention involves various other features of importance, all of which will be fully set forth hereinafter and particularly pointed out in the claims.

Reference is to be had to the accompanying 40 drawings, which represent as an example the preferred embodiment of the invention and in which drawings—

Figure 1 is a diagram showing the arrangement of the system; Fig. 2 is a detailed section showing the vaporizing arrangement for the starting gasoline; and Fig. 3 is a sectional view showing the preferred form of distributing valve.

45 The invention is adapted especially to multiple cylinder four-cycle engines, and in Fig. 1, 10 indicates three cylinders of such an engine. The number of cylinders is not material. In the compression space of each cylinder a pipe 11 leads carrying air under pressure. Other fluids under pressure might be employed, providing they are

not of such a nature as will interfere with the nature of the operations hereinafter described. The air pipes 11 communicate with a distributing valve 12. I will herein- 60 after describe the specific form of such a valve which I prefer to employ, though particularly the form of this valve is not material to my invention. The valve may be of any of the known types in which it is 65 geared with the engine in such a manner as to open the compressed air supply successively to the pipes 11, according as said pipes are in communication with cylinders, the pistons of which are in position to per- 70 form their power or working stroke. As the valve 12 rotates, therefore, under the movement of the engine, it successively opens the air supply to the pipes 11 at the times that the cylinders with which the 75 pipes communicate have their pistons in firing position. In short, the arrangement is such that by connecting the valve 12 with a compressed air supply and operating the valve, the engine would thereby be caused 80 to operate as a compressed air motor.

14 indicates a pump driven from the engine or otherwise and compressing air in a storage tank 15 from which a pipe 16 leads to the receiving port of the valve 12. 85

17 indicates a globe valve or other means for opening or closing the pipe 16.

The valve 12 is arranged, by its mechanical connection with the engine, so that when the engine stops one of the pipes 11 is 90 opened to the air supply, such pipe being that which communicates with the port cylinder of the engine, the piston of which is in position for firing. Therefore, when the engine is at rest, by opening the valve 95 17 and admitting compressed air to the inlet port of the valve 12, this air will be conducted to the engine cylinder, the piston of which is ready to work and, upon the air exerting itself on this piston, the engine is 100 caused to move. This imparts motion to the valve 12 and instantly thereafter another pipe 11 is opened to the compressed air supply, this other pipe 11 being that which communicates with the cylinder, the 105 piston of which follows the first piston in its working stroke and so on, the operation being in such a manner that the engine will operate as an air motor as long as the air supply in the tank 15 lasts. Of course, it 110 will be understood that in the normal operation of the engine under gasoline, the pump

14 is operated to keep a sufficient supply of compressed air ready at all times.

18 indicates a gasoline tank, which may or may not be the supply tank of the engine. 3 To this tank air pressure is communicated by a pipe 19 from the tank 15 or any other source, and 20 indicates a valve by which the movement of pressure to the tank 18 may be regulated. From the tank 18 a 10 gasoline pipe 21 passes with branches 22 leading up to cylinder passages 23 opening into the seats of the inlet valve 25 of the respective cylinders 10 or directly into the cylinder. These valves 24 when seated 15 close the nozzles 23, but when the valves 24 are moved from their seats, the nozzles are uncovered and the gasoline from the tank 18 under the pressure of the air therein is caused to be ejected as a jet against the inlet 20 valve in the port leading to the working chamber of the cylinder. Preferably these nozzles 23, as shown in detail in Fig. 2, are controlled by needle valves 25, which have blunt points adapted, when the valves 25 are shut, to lie coincident with the seats of the valve 24, thus not only placing said nozzles 23 under control, but allowing the valve seats to be ground without danger of clogging said nozzles. The inlet valve 24 25 controls the usual communications with the carburetor of the engine, 26 indicating, for example, the carburetor manifold or other connecting medium.

Assuming now that air is stored in the 35 tank 15 and the valve 17 is open, air will then flow direct to the cylinder 10 which has its piston rod to move downward on the working stroke. The compressed air will, therefore act on this particular piston and 40 force it downward. This will cause the engine to operate as an air motor. Then upon opening the valve 20, the pressure communicated to the tank 18 will cause jets of gasoline to be introduced into the inlet parts 45 of the engine at such of said ports in which the valves 24 are open. These inlet valves 24 open in the usual succession of the operation of the engine and, therefore, gasoline priming charges are drawn into the working 50 chambers in accordance with the engine cycle. The sparking or other igniting system being in operation, these priming charges will be exploded and gradually the engine will begin to operate not simply as 55 an air motor but as an explosive engine under priming charges. The valve 17 may now be closed, for the engine will operate under the gasoline from the tank 18 and in so doing will gradually draw from the carburetor the normal charges which will be 60 taken up and exploded in their order, and at this time the operation of the engine will become normal, excepting for the priming charges, which may be closed off, shutting 65 the valve 20 or otherwise depriving the tank

18 of its air pressure. It should be understood that during this operation the valves 25 are open. They may be left open, in fact, during the normal operation of the engine, but it is considered preferable to close them, as by so doing their seats will be kept free 70 from dirt from the engine; and it is considered particularly desirable to close them when repair work is being done on the engine, such, for instance, as grinding the 75 valve seats. The pressure in the tank 18 is used only to lift the gasoline, so that it becomes immaterial as to just how this pressure is communicated. It may, in fact, be gravity pressure without the aid of air, depending upon the arrangement of the power plant, whether it be in an automobile plant 80 or in some other connection.

Fig. 3 shows a construction of the distributing valve 12, which avoids incessant 85 and unnecessary wear on the moving parts. The shaft 27, it will be understood, must rotate with the engine shaft, usually at half the speed thereof, and it is provided with a squared portion 27^a, on which a disk valve 28 is arranged, so that the valve turns with the shaft but may move freely thereon, axially on the shaft. A light spring 29 is employed to throw the valve 28 away from the seat 12^a of the distributing valve. This 90 seat has a vent 12^b and a number of ports 12^c which communicate respectively with the pipe 11. The disk valve 28 has a single port 28^a, and below the disk valve the air supply pipe 16 enters the valve casing 12. 100 When the valve 17 is closed, the spring 29 throws the disk valve 28 away from its seat, and the valve turns idly in the casing. When, however, pressure is admitted below the disk valve, it throws the disk valve rapidly to its seat. There will be a certain leakage of pressure through the port 28^a, it is true, but owing to the proportions of the ports, this will not be sufficient to prevent the valve 28 from moving up to its seat 110 as described. The vent 12^b is thereby closed, but the port 28^a of the rotating disk 28 runs in the path of the ports 12^c and successively opens them to communication with the pipes 11, supplying the air to the cylinders in the 115 manner described. As soon as the valve 17 is closed, the pressure in the pipe 16 is exhausted and a spring 29 returns the disk valve to its inactive position. This is repeated continuously during the normal 120 operation of the engine, and the valve 28 simply spins around in the casing without any unnecessary wear on any of the parts.

While I have specifically described my invention as applied to an engine of the puppet valve type, I desire it understood that it is not so limited and that its principles are applicable to any internal combustion engine, among which may be enumerated the sliding sleeve valve type.

Having thus described my invention, what I claim as new and desire to secure by Letters Patent is:

1. The combination with an internal combustion or gasoline engine of means for starting the engine by air or other fluid under pressure and means controlled by the position of the inlet valve of the engine for injecting priming charges into the working cylinders during the operation of the cylinders under air pressure.
2. The combination with an internal combustion or gasoline engine of means for starting the same by air or other fluid under pressure, means for leading a priming supply of fuel to the seats of the inlet valves, the ports of such priming charges being closed by the valves near their seat, whereby priming charges are introduced into the engine simultaneously with its operation under said air pressure for the purpose specified.
3. The combination with an internal combustion or gasoline engine of means for starting the same by air or other fluid under pressure, means for leading a priming supply of fuel to the seats of the inlet valves, the ports of such priming charges being closed by the valves near their seat, whereby priming charges are introduced into the engine simultaneously with its operation under said air pressure and valves for closing said priming charge ports or nozzles for the purpose specified.
4. The combination with an internal combustion or gasoline engine of means for starting the same by air or other fluid under pressure, means for leading a priming supply of fuel to the seats of the inlet valves, the ports of such priming charges being closed by the valves near their seat, whereby priming charges are introduced into the engine simultaneously with its operation under said air pressure and valves for closing said priming charge ports or nozzles, such valves being of the handle type with blunt points coinciding when the valves are closed with the faces of the inlet valve seats.
5. The combination with an internal combustion engine, of means for starting the same under compressed air, means for simultaneously supplying combustible, but themselves non-explosive, priming charges to the cylinders, and a carburetor communicating with the cylinders to supply the normal charges, said engine comprising means controlling the supply of such priming charges and arranged to admit such priming charges successively during the admission period.
6. The combination with an internal combustion engine, of means for starting the same under air or other combustion-supporting fluid under pressure, means for simultaneously supplying combustible, but themselves inexplosive, priming charges of fuel to the engine cylinders, and a normal fuel supply communicating with the engine cylinder, said engine comprising means controlling the supply of such priming charges and arranged to admit such priming charges successively during the admission period, whereby the engine may be first operated by compressed air, and will successively take up its operation under the priming charges and then under the normal fuel charges.

In testimony whereof I have signed my name to this specification in the presence of two subscribing witnesses.

WILLIAM H. SCHOONMAKER.
